US00D852654S

(12) United States Design Patent (10) Patent No.: US D852,654 S
(45) Date of Patent: * Jul. 2, 2019

(54) DIGITAL THERMOMETER

(71) Applicant: Shenzhen Goldgood Instrument Limited, Shenzhen (CN)

(72) Inventor: Kui Zou, Loudi (CN)

(73) Assignee: Shenzhen Goldgood Instrument Limited, Shenzhen (CN)

() Term: 15 Years

(21) Appl. No.: 29/685,015

(22) Filed: Mar. 26, 2019

(51) LOC (11) Cl. 10-04

(52) U.S. Cl.

USPC D10/57

(58) Field of Classification Search

USPC D10/57, 58

CPC G01K 2207/02; G01K 2207/04; G01K 2207/06; G01K 2207/08

CLAIM

The ornamental design for a digital thermometer, as shown and described.

DESCRIPTION

FIG. 1 is a perspective view of a digital thermometer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the digital thermometer that form no part of the claimed design.

1 Claim, 8 Drawing Sheets
